UNITED STATES PATENT OFFICE

FRANK J. DOUGLASS, OF CHICAGO, ILLINOIS

RADIATOR HANGER

Application filed August 29, 1929. Serial No. 389,197.

This invention relates to means for hanging radiators on the walls of buildings, this arrangement having recognized advantages over the method of standing the radiators on the floor, but presenting certain difficulties which have limited the practice very considerably.

One of the objects of the invention is to so arrange the hollow bricks of a wall composed of bricks of this type so that the voids may be utilized for the attaching devices employed for securing the radiator hangers to the wall.

Another object is to provide a radiator hanger that may be attached to the wall of a building before the wall has been plastered. This expedient obviates the necessity of a temporary installation in the building of radiators where heat is required before the plastering and carpenter work is completed.

Other incidental objects of the invention will be referred to in the following description of the preferred embodiment of the invention disclosed in the accompanying drawings.

In the drawings:

Fig. 1 is a front elevation of a radiator supported from the wall in accordance with this invention.

Fig. 2 is a front elevation of the radiator hanger shown as attached to the wall, the radiator shelf not being shown in this view.

Fig. 3 is a sectional view on line 3—3 of Fig. 2.

Fig. 4 is a sectional view on line 4—4 of Fig. 1.

Fig. 5 is a view in perspective of the hanger.

Fig. 6 is a sectional view similar to Fig. 4 illustrating a modification; and

Fig. 7 is a sectional plan view of a hanger embodying the invention in a different form.

Referring first to Figs. 1 to 5 inclusive: 10 designates one of the walls of a building and 11 the floor. The wall consists of hollow bricks 12, the voids 13 of which, as is usual, 15 extend longitudinally through the bricks. These bricks are for the most part laid lengthwise of the wall in two series of courses 14, 15. It is customary to introduce occasionally a header course in which the bricks are laid 20 transversely of the wall. According to my

invention this header course is arranged so that it will be at the level of the radiator or radiators which it is intended to support on the wall, by which I mean at a predetermined level suitable for attachment of the means for supporting the radiator, the bricks of the header course being designated 16, (Figs. 3 and 4) because of their transverse arrangement in the wall, the voids 17 of these bricks are exposed on the inner surface of the wall.

The radiator hanger consists of a back plate 18 formed, preferably, with inturned flanges 19 having bonding perforations 20 for the plaster with which the wall will be covered. Secured to the back plate 18, preferably by means of their angular flanges 21 are a pair of brackets 22 formed with curved recesses 23 on their upper edges. The radiator 24 which is made up of a series of sections 25 provided with abutting bosses 26, is supported on the brackets 22, the bosses 26 seating in the grooves 23.

The supply pipe for the radiator 24 is indicated at 27 and the return pipe at 28. Secured to the back-plate 18 of the hanger are a pair of horizontally arranged angle bars 29, 30 which space the radiator away from the back-plate. Below the angle bar 29 the back-plate is pierced with a pair of oblong openings 31. Preferably expansion bolts are provided for fastening the back-plate to the wall, these devices being designated 32 and extending through a pair of washer plates 33 and through the apertures 31 into the voids 17 in the header course of bricks 16. The washer plates 33 have eccentrically arranged openings for bolts 32 to permit the vertical and horizontal adjustment and leveling of the hanger in view of possible irregularity in the positions of the bricks of the header course.

For example the washer plate may be oblong and the openings at distances from the edges of the plate which are different by a quarter or eighth of an inch. The upper angle bar 29 rests upon the upper edges of the washer plates 33.

The radiator bracket may be secured to the wall of the building before it is plastered. Referring to Figs. 3 and 4, 34 designates the lathing and 35 the plaster. The latter en-

ters the perforations 20 in the flanges 19 sufficiently to provide a bond.

If desired the flanges may consist of separate angle bars 36 (as shown in Fig. 7) secured to the back-plate 37 and the webs of the angle bars may be at an acute angle to each other for the purpose of making a better joint and bond between the plaster and the hanger structure.

10 If desired the back-plate of the hanger may extend substantially from the window sill to the floor as indicated in Fig. 6 in which the back-plate 38 extends back of the lower molding 39 of the window sill 40 and also 15 back of the base board 41.

One serious objection to having the radiators of a building hung from the wall is the difficulty and expense of providing a secure anchorage of the hangers to the wall. Drilling 20 of the bricks of the wall has been resorted to but that involves expense and frequently results in cracking the bricks so that they have to be removed and new bricks put in their place.

25 The expedient of providing at the radiator level a header course of hollow bricks with their voids exposed very greatly simplifies the procedure in making the necessary attachments of the hanger to the wall. By the 30 adjusting arrangement described the hanger can be raised or lowered at one end or at both ends in order to level it and give it a uniform elevation with other radiators in the room even though the bricks of the header course 35 should be slightly out of alignment with each other and can also be adjusted horizontal to center it under the window.

Ordinarily where it has been found necessary to heat a building before the plastering 40 and carpenter work is done it has been customary to install the radiators temporarily in positions away from the wall until such time as the wall has been lathed and plastered and carpenter work such as placing of the base 45 board has been completed. The piping of the radiators is then disconnected and the radiators put in their proper places and the permanent connections made. This procedure involves very considerable expense and some 50 interference with the work of the artisans and is a procedure which is quite impractical if the radiators are of the type intended to be ultimately supported on the walls of the buildings.

55 My invention obviates these difficulties by a procedure which involves securing the radiator hangers immediately to the brickwork which permits the radiators to be put in place, if need be, before the plaster work is started. The plasterer does not have to plaster the wall behind the radiators, except up to the back plate of the hangers, and this back-plate may be made as large as may be desired. The radiators once put in place

need not be removed or their connections changed.

The back-plate provides a dead air space directly back of the radiator which forms an insulating medium to prevent heat loss 70 through the wall.

The flanges on the back-plate instead of being integral therewith may be made separately, for example, of cast iron and built into tile or brick wall, and face plate bolted on 75 after wall is built.

Realizing that the invention may be modified in respect to details of construction, I desire to be understood as intending to cover all constructional changes within the scope 80 of the appended claims.

I claim:

1. A radiator hanger comprising in combination an apertured back-plate provided with a projecting portion, radiator brackets 33 on said back-plate, attaching devices for the back-plate extending through the apertures therein and washers having openings for the attaching devices eccentrically arranged for adjustment and adapted to be engaged by the 38 projecting portion of the back-plate.

2. A radiator hanger comprising a back-plate, radiator supporting brackets on said back-plate, means providing an outstanding web between said brackets, the back-plate being apertured below said web, attaching devices for the back-plate adapted to extend through said apertures and polygonal washers eccentrically perforated for said attaching devices, said web resting on said washers 435 to support the back-plate.

3. A radiator hanger comprising a back-plate, radiator brackets thereon, means providing a forwardly projecting web between said brackets, the back-plate being apertured 485 below said web, attaching devices comprising portions adapted to extend freely through the apertures and be anchored in a wall, and also comprising plate portions adapted to overlap the apertures and having edge portions positioned eccentrically with respect to the first portions, said edge portions being selectively engaged beneath the web to determine the vertical positioning of the back-plate.

4. A radiator hanger comprising a back-plate provided with inturned perforated marginal flanges, radiator supporting brackets on said back-plate, a pair of horizontal angle bars secured to the back-plate between 530 said brackets, the back-plate being formed with apertures under the upper angle bar, expansion bolts for attaching said back-plate to a wall which extend through said apertures and polygonal washer plates perforated 555 for the expansion bolts at a place which is at different distances from the several edges of the plate in each case.

FRANK J. DOUGLASS.
